ATTORNEY

UNITED STATES PATENT OFFICE

ALEXANDER K. SUTHERLAND, OF MILWAUKEE, WISCONSIN, ASSIGNOR TO MOE-BRIDGES COMPANY, OF MILWAUKEE, WISCONSIN, A CORPORATION OF WISCONSIN

SHADE HOLDER

Application filed August 24, 1927. Serial No. 215,168.

This invention relates to shade holders and has for its object to provide a shade holder with shade clamping means that will positively lock the shade against removal without danger of injury thereto and without impairing the ornamental appearance of the shade holder.

Another object of the invention is to provide such a clamping mechanism for shade holders that will be simple in its construction and inexpensive to manufacture without involving material change of the shade holder shell.

Another object of the invention is to provide a shade holder with a lamp socket attaching means that will be simple in its construction and that will be firmly and rigidly held in place against independent movement.

With the above and other objects in view the invention consists in the shade holder, its parts and combinations of parts as herein claimed and all equivalents.

Referring to the accompanying drawings in which like characters of reference indicate the same parts in different views,

Fig. 1 is a central sectional view of a shade holder constructed in accordance with this invention;

Fig. 2 is a bottom view thereof with the shade and lamp removed;

Fig. 3 is a detail sectional view on line 3—3 of Fig. 1 showing the manner of securing the lamp socket yoke against turning;

Fig. 4 is a sectional detail view of one of the shade clamps; and

Fig. 5 is a perspective view of the locking lever and its washer.

In these drawings 10 indicates the shell member of usual ornamental shape having a supporting ring 11 passed through the center with a nut 12 threaded thereon, as usual. An arch-shaped yoke member 13 curved to fit the curvature of the top of the shell member is mounted therein by having a central opening fitting over the threaded tubular stem of the ring member and is clamped in place by the nut 12. The shell member has slits cut in it in line with the edges of the yoke member 13 and the metal at the sides of the

slits is pressed inwardly to form projecting lugs 14 engaging the edges of the yoke member to prevent it from turning, as best seen in Fig. 3. This enables the lamp 15 to be threaded in and out of its socket 16, which is secured between the ends of the yoke member, without the turning of the yoke in the shell member.

The clamps for the flaring neck of the shade 17 consist of spring tongues 18 attached to the shell member 10 by single rivets 19 with their upper ends bent to engage the shoulder 20 of the shell member to prevent the tongues from swinging on the rivets, said tongue members having their lower ends bent upwardly to form yielding engaging means for engaging the neck of the shade. The tongue members are moved inwardly and held in their clamping engagements by angular locking levers 21 passed through openings near the edge of the shell member and capable of swinging from a closed position as shown at the left in Fig. 1 to an open position, as shown at the right in Fig. 1.

The locking lever is formed of a narrow stem portion which is bent to give it the angular shape and an enlarged head or cam portion 22 preferably rectangular in shape for engaging the spring tongue 18, and to avoid wear of the bearing shoulders of the enlarged head 22 on the thin shell member 10, a steel washer 23 is loosely mounted on the stem so that the shoulders bear on it.

When the lever is in its open position the head 22 is upright and the spring tongue 18 is released permitting the flaring edge of the shade neck to freely pass for entering the shade in the holder or for removing it therefrom, but when the lever is swung upwardly to its closed position the head acts as a cam pressing the lower end of the tongue member inwardly for tightly locking the shade against removal and yieldingly holding it against independent movement.

The pressure of the spring tongue against the locking lever is incapable of urging it to its open position, since the head 22 thereof passes its dead center position before reaching the locked position and the stem portion bears directly against the shell. When so

locked in place the shade cannot be removed and the narrow lever stems are unnoticeable as they bear against the shell but they are easily manipulated for releasing or locking the shade.

- 5 6 To facilitate the entry of the flaring neck of the shade between the spring tongues 18 and prevent it from passing between the spring tongues and the shell, each spring tongue has a projection 24 cut therefrom and 10 extending outwardly from its bent lower end to engage the shell beneath the loose washer.

15 The shade holder of this invention is simple in its construction and inexpensive to manufacture, provides for fixing the lamp socket against rotation and for mounting the shade clamps without material alteration of the shell member, and affords a shade clamp construction that is strong and durable and 20 highly efficient for preventing the withdrawal of the shade even when force is exerted thereon. It is neat and ornamental in its appearance and positive in its action, with no screw threads to become stripped, no soldered parts 25 to become loose and no frail connections to wear.

What I claim as new and desire to secure by Letters Patent is:

- 30 1. A shade holder, comprising a shell provided with a shoulder, spring tongues riveted to the shell and having bent ends engaging the shoulder and having their other ends bent to form yielding shade engaging portions, angular locking levers with stems extending 35 through openings in the shell member and with enlarged heads forming shoulders, washers on the stems between the shoulders and the shell member, said heads engaging the spring tongues to force them inwardly, 40 and lugs bent out from the spring tongues to engage the shell member and block the space between the spring tongues and the shell member.

- 45 2. A shade holder, comprising a shell member, spring tongues secured thereto, angular locking levers extending through openings in the shell member and having shoulders bearing inside the shell member, said locking levers engaging the spring tongues for moving 50 them inwardly, and lugs on the spring tongues engaging the shell member for blocking the space between the spring tongues and the shell member.

In testimony whereof, I affix my signature.
55 ALEXANDER K. SUTHERLAND.
